UNITED STATES PATENT OFFICE.

GEORGE W. BLAKE, OF WYANDOTTE, MICHIGAN, ASSIGNOR TO THE GEO. W. BLAKE MFG. COMPANY, OF WYANDOTTE, MICHIGAN, A CORPORATION OF MICHIGAN.

RECEPTACLE-FILLING MACHINE.

Application filed October 12, 1922. Serial No. 594,015.

This invention relates to a receptacle filling machine of that class disclosed by my Patent No. 1,278,097, granted Sept. 10, 1918, and in my pending application filed June 4, 1920, Serial No. 386,529. The machine includes, inter alia, filling means for receptacles; electro-mechanical means controlling the filling means; movable platforms to receive the receptacles; means successively actuated by the placing and filling of receptacles on the platforms for controlling the operation of the electro-mechanical means, and means to move the platforms with the receptacles thereon so that the receptacles may be removed.

This invention particularly relates to an improvement in the filling means for the receptacles, also, the means actuated by the placing and filling of receptacles for controlling the operation of the electro-mechanical means, which in turn controls the filling means.

Considering the first improvement, this invention includes a feeding device for each filling spout of the machine and an agitator that will serve all of the filling spouts of the machine. The feeding device will positively prevent clogging, jamming, and material formations that will retard the progress of any material through the spouts, particularly such tacky, adhesive or solidifying materials as caustic soda, potash, chloride of lime etc., and the agitator will stir the material in the reservoir and insure an uninterrupted flow of the material into the filling spouts. Since the filling spouts are opened and closed by electro-mechanical means, the feeding devices are arranged to be operated in timed relation to the opening and closing of the filling spouts so that the feeding devices will be operated only when the spouts are open. Closing of the spouts or inactivity of the machine may cause material in the spouts to settle and become packed therein, but immediately upon opening the spouts and placing the feeding devices in operation the material is caused to freely flow. Then again, the feeding devices may be of such a size and so located relative to the feeding spouts that approximately a predetermined quantity of material will be fed through the spouts, and when the feeding of material is pro-

tioned to the weight of material desired there will be a minimum waste and less burden on the scales of the machine.

My next improvement is a quick release device for a switch which is employed in connection with the steel platforms for breaking an electrical circuit after a receptacle had received a predetermined quantity of material. In order that the scales or weighing platforms could quickly control the operation of the electro-mechanical means, which in turn controlled the filling means or spouts of the machine, I found it advantageous to use a solenoid actuated switch and this refinement in the electrical control of the machine contributes to the high degree of perfection obtained in the machine now in use.

The present improvements will be herein-after more fully described, and reference will now be had to the drawings, wherein

Figure 1 is a horizontal sectional view of a portion of the machine showing the scales or weighing platform;

Fig. 2 is a vertical sectional view of the greater portion of the machine;

Fig. 3 is an enlarged side elevation of a portion of the machine illustrating the filling and feeding means for receptacles;

Fig. 4 is an enlarged side elevation of one of the scales or weighing platforms illustrating the solenoid actuated switch and electrical connections;

Fig. 5 is a top plan of the machine partly broken away and partly in section;

Fig. 6 is a diagrammatic view illustrating the electrical wiring of the machine, and

Fig. 7 is a horizontal sectional view of the mechanical means of controlling a filling spout of the machine.

My machines includes a base 1 and uprights 2, 3 and 4 with the upper ends thereof connected by a three-arm spider 5. The uprights are otherwise connected, particularly by a three-arm spider 6, adjacent the base 1 of the machine and this spider cooperates with the spider 5 in providing bearings or journals for a vertically disposed drive shaft 7 which may be operated from an electric motor or suitable source of power.

Mounted on the vertical shaft 7 is a bottom plate or platform 8 and secured to said bottom plate are lateral flanges 9 of a plu-

rality of inverted frustro-conical shaped chutes 10 communicating with openings 11 in the bottom plate 8. Connected to the lower face of the bottom plate 8, about the 5 openings 11, are filling spouts 12 corresponding in number to the chutes 10 with the walls of said filling spouts practically a continuation of the walls of the chutes 10. Suitably connected to the lower ends of the 10 filling spouts 12 are flexible discharge tubes 13 that may be in the form of pieces of hose that may be collapsed or have walls thereof pressed towards each other to restrict the passage to the tube or completely close the 15 same.

Between the upper ends of the chutes 10 is a horizontally disposed wall 14 and suitably connected to the side edges of this wall and the side edges of the chutes 10 are the 20 inner and outer annular walls 15 and 16 respectively of an auxiliary reservoir, said walls cooperating in providing an annular compartment normally closed by a cover plate 17 suitably attached to the spider 5. 25 The cover plate 17 has a detachable hand-hole plate 18 and an opening 19, said opening admitting material to the auxiliary reservoir from a main reservoir (not shown).

Mounted on the marginal edges of the 30 bottom plate or platform 8 are bearings 20, corresponding in number to the chutes 10 and journaled in said bearings are shafts 21 provided with gear wheels 22. Pivoted on the shafts 21 are yokes 23 supporting rotatable pinions 24 constantly meshing with the gear wheels 22 and adapted to mesh with a substantially circular rack 25, carried by brackets 26 attached to the uprights 2, 3 and 4.

35 The shafts 21 extend into the chutes 10 and closed gear housings 27 mounted within said chutes. The gear housings 27 are provided with depending feeder shafts 28 and on the upper ends of said shafts are beveled gear wheels 29 constantly meshing with beveled gear wheels 30 on the shafts 21. On the lower ends of the shafts 28 are spiral feeders or screws 31 adapted to loosen material in the lower ends of the chutes 10, in 40 the filling spouts 12, and the upper ends of the discharge tubes 13 and if the material does not descend by gravity it may be fed out of the chutes 10 into the discharge tubes 13 by the feed screws which are adapted to 45 be driven when the pinions 24 mesh with the rack 25 and the auxiliary reservoir rotated relative to the stationary rack 25.

50 In addition to the feeders within the chutes and filling spouts, I employ an agitator for stirring up the material in the upper ends of the chutes 10 and the auxiliary reservoir adjacent the chutes which are active. The agitator comprises a star wheel or 55 multi-pointed member 32 having its points or tips provided with shields 33. The wheel

or member 32 is rotatable in a forked lever or arm 34 pivotally connected to a depending bearing 35, carried by a cover plate 17, but more especially the hand-hole plate 18 which will permit of the agitator being bodily removed. Connected to the arm 34 is a suspension rod 36 extending through an opening 37 in the plate 18, said suspension rod being slidable in a bracket 38 mounted on the plate 18. Encircling the suspension 70 rod 36, between the bracket 38 and a collar 39 on the rod 36 is a coiled expansion spring 40 which yieldably holds the agitator wheel or member in a lowered position, so that the arms or spokes of the agitator will extend 75 into the chutes 10, said arms or spokes spanning the wall 14 between the chutes and the gear housings 27 within the chutes, as the auxiliary reservoir is rotated. By the walls of the chutes 10 and the gear housings 27 80 contacting with the shields 33 of the agitator it will be revolved and thus agitate or stir material in the chutes 10 and the auxiliary reservoir.

Attached to the lower face of the bottom 85 plate or platform 8, below each bearing 20, is a hanger 41 supporting a set of solenoids 42 having cores 43 thereof connected by a cross head 44, and rigidly attached to said cross head and extending through the bottom plate or platform 8 is a rod 45 connected to the end of the yoke 23 by a link 46 which permits of the solenoid when energized rocking the yoke 23 to shift the pinion 24 thereof 90 into mesh with the stationary rack 25. Attached to the cross head 44, between the solenoids 42 is a plunger 47 encircled by a coiled expansion spring 48 which raises the cross head 44, rock yoke 23 and retracts the 95 pinion 24 relative to the rack 25 when the 100 solenoids 42 are deenergized.

Suitably attached to each hanger 41 are brackets 49 having confronting channel guides 50 and slidably in said channel guides are the ends of opposed shut off members 51 110 and the ends of rods 52. The shut off members 51 are in opposed relation at the sides of the discharge tube 13 and said shut off members have presser blocks adapted to collapse the walls of the discharge tube and close or 115 restrict the passage through said tube. The shut off members 51 are best shown in Figs. 2 and 7 and are connected by links 53 to the rods 52; also by toggle members 54 which are pivotally connected to the ends of a fork 120 55 fulcrumed on a pin 56 connecting the brackets 49, said fork being pivotally connected to the lower end of the plunger 47.

125 The shut off devices in the solenoids which operate the same have been described in my prior Patent No. 1,278,097 as electromechanical means controlling the discharge tubes which constitute filling means for receptacles placed below the discharge tubes, and 130 before describing the operation of the rotary

feeding devices controlled by the solenoids, I will describe my improvement in connection with the scales or weighing platforms on which receptacles are placed and adapted 5 to be filled with material from the discharge tubes 13.

As in my former patent, the shaft 7 is provided with a rotary carrier 57 which has its peripheral edges cut away to provide 10 clearance for a plurality of scale platforms 58 corresponding in number to the discharge tubes 13. Each scale platform has a depending stirrup 59 pivotally connected to a yoke 60 on the outer end of a scale beam 61. 15 The yoke 60 is pivotally connected to a stirrup shaped hanger 62 of the carrier 57 and this hanger is connected by a link 63 to the yoke 59. The constructive arrangement of the scale beam 61 is such that it is normally maintained in a horizontal plane 20 below the peripherial edges of the rotary carrier 57, and with the scale platform of the beam and poise type it is possible to set the poise of the scale so that the platform will not be overbalanced until a predetermined quantity of material has entered a can or receptacle on the platform.

Above each scale platform 58 is a fixed abutment 64 and a yieldable abutment 65 constituting a receiving means for a receptacle to be placed on the platform, and between said abutments is a conventional form of push button switch 66 adapted to be actuated by a receptacle.

On the lower face of each scale platform 58 is an insulated contact member 67 adapted to engage an adjustable contact member 68, when the platform is depressed, said adjustable contact member 68 being carried by a bracket 69 secured to the lower face of the rotary carrier 57, as best shown in Fig. 4. Adjacent each bracket 69 is a support 70 for a solenoid 71 having a core 72 connected by a link 73, to a switch arm or blade 74. The upper end of the switch blade is pivotally connected to a switch block 75 attached to the lower face of the rotary carrier 57, said switch block having blade guides 77 and contact members 76 for the switch blade 74. 45 There is a solenoid and switch for each scale platform, but for the sake of clearness I have only shown one solenoid and switch in dotted lines in Fig. 1, but it is to be understood that such equipment is adjacent each 50 scale platform.

Suitably fixed on the three-arm spider 6 is a brush holder 79 having brushes 80 and 81 in circuit with a suitable source of electrical energy (not shown). The brushes 80 and 81 contact with distributor rings 82 and 83 respectively carried by an insulator 78 mounted on the vertical drive shaft 7, and the distributor ring 82 is connected by insulated electrical conductors 84 to binding post 85 on the rotary carrier 57, said bind-

ing post being connected by conductors 86 to the switches 66. The switches are connected by conductors 87 to binding posts 88 on the rotary carrier 57 and by conductors 89 to the switch blades 74 below the rotary carrier 57. The contact members 76 of each switch are connected by a conductor 90 to the solenoid 71 and said solenoid by a conductor 91 to the bracket 69 extending below each scale platform 58. The insulated contact member 67 of each scale platform is connected by a conductor 92 to a binding post 93 on the rotary carrier and this binding post is connected by a conductor 94 to the distributor ring 83 and by a conductor 95 to the set of solenoids 42 above the scale platform 58, said solenoids being connected by a conductor 96 to the switch contact member 76. By reference to Fig. 2 it will be noted that the conductors 95 and 96 extend through an insulator 97 of the rotary carrier 57 and an insulator 98 on the drive shaft 7.

Suitably supported from the upright 4 and the platform 102 is a rail 99 adapted to be engaged by shoes 100 carried by the scale platforms 58, said shoes elevating the platforms by engaging the rail, after the receptacles are filled, thus placing the scale platforms flush with the rotary carrier 57 and the platform 102 to permit of the scale platforms being easily loaded and unloaded.

The rail 99 has a handle provided with an inwardly projecting pin 101 which is in the path of the switch plate 74 said switch plate contacting with a pin 101 to close the switch after it has been opened by the solenoid 79.

In order that this machine may be considered as complete, I have illustrated the following elements or structures which are fully described in my pending application.

100 105 102 is a loading and unloading platform provided with a loading endless conveyor 103 and an unloading endless conveyor 104.

105 110 107 is an adjustable swingable loading arm supported from the platform 102 and through the medium of a suitable mechanism adapted to be actuated by trip members 106 depending from the rotary carrier 57.

110 115 107 is an abutment on the platform 102 which retains receptacles on the loading conveyor 103 until such time as the scale platform is in position to receive a receptacle.

115 120 108 are guide rails, one of which has an adjustable guide 109, these guides facilitating loading and placing of receptacles on the scale platforms 58 relative to the abutments 64 and 65 and the switches 66.

120 125 110 are guide rails for the unloading conveyor 104.

Besides the above enumerated devices 130 there is a vibratory device, guides and va-

rious instrumentalities which contribute to a machine that does expeditiously and economically fill receptacles, and the operation of my machine, particularly the improved parts, will now be considered.

Assuming that the drive shaft 7 is driven from a suitable source of energy, the rotary carrier 57 and the auxiliary reservoir are revolved in unison in a clockwise direction. The material in the auxiliary reservoir is stirred or agitated by the wheel or member 32 so that the material will enter the chutes 10 and may descend by gravity into the discharge tubes 13. When these tubes are open for filling receptacles the solenoids 42 are energized and the screw feeders are operated by virtue of the pinions 24 engaging the stationary rack 25. The energizing circuit of the solenoids 42 is shown in Fig. 5 and is as follows;

The distributor ring 82 by wire 84 to the binding post 85 by a conductor 86 to the switch 66, which is closed by a receptacle being placed on the scale platform. From the switch 66 by a conductor 87 to the binding post 88 and by conductor 89 to the switch blade 74. The switch blade being in a closed position the circuit continues by contact members 76 and conductor 90 to solenoid 42 and then by conductors 95 and 94 to the distributor ring 83. With the solenoid energized the receptacle is being filled as the carrier 57 and the auxiliary reservoir are revolved, and any tendency of the material to clog the discharge tube 13 is prevented by the screw feed within the discharge spout 12 and the tube 13.

When the receptacle receives a predetermined quantity of material the contact member 67 of the scale platform engages the adjustable contact member 68 and the following circuit is completed.

From distributor ring 83 by conductors 94 and 92 through the contact members 67 and 68, bracket 69 to conductor 91 leading to the solenoid 71, by conductor 90 to contact member 76, knife blade 74 and conductors 89 and 87 to switch 66, which is still closed because of a loaded receptacle against said switch. From this switch by conductors 86 and 84 to distributor ring 82. This circuit energizes the solenoid 71 and retracts the switch blade 74, so that the solenoid 42 is de-energized and the expansive force of the spring 48 may close the shut off members 51 and retract the pinion 24 relative to the stationary rack 25. This takes place when a receptacle has received a predetermined quantity of material, and when the filled receptacle is removed from the scale platform all circuits are broken, in connection with this particular scale platform until the same receives an empty receptacle.

It is thought that the utility of my improvements will be apparent without further

description, and it is to be understood that such improvements are susceptible to such changes as are permissible by the appended claims.

What I claim is:—

1. In a filling machine adapted to receive receptacles, a rotary reservoir, filling means for the receptacles, electro-mechanical means controlling said filling means, a material feeding device extending into said filling means, means carried by said rotary reservoir and controlled by said electromechanical means for causing operation of said material feeding device, and means controlled by the weight of a receptacle and its contents in said machine for controlling the actuation of said electromechanical means. 70

2. A filling machine as in claim 1 wherein in said filling means includes a collapsible tube adapted to be closed or have its passage restricted by said electro-mechanical means. 75

3. In a filling machine, a rack, a rotary reservoir, a discharge tube depending from said reservoir, a feeding device in the upper end of said tube, closing means for the lower end of said tube, means controlled by the weight of a receptacle and its contents for actuating said closing means, and means controlled by said closing means adapted to cause operation of said feeding device from said rack. 80

4. A filling machine as called for in claim 3, wherein the last mentioned means includes shafts, gear wheels, a tiltable yoke, and a pinion carried by said tiltable yoke and adapted to mesh with said rack. 100

5. A filling machine as called for in claim 3, wherein said closing means includes electrically opened shut off members adapted to be automatically closed. 105

6. In a filling machine, a rotary reservoir, a discharge tube communicating with said reservoir, normally closed shut off members closing said tube, a feeding device in said tube, electrical means adapted to open said shut off members and place said feeding device in condition to be operated, and means adapted to rotate said reservoir, said means being controlled by the weight of a receptacle and its contents in said machine for causing operation of said feeding device. 110

7. In a filling machine adapted to receive receptacles, mechanically closed and electrically opened filling means for the receptacles, platforms to receive the receptacles and adapted to be lowered and raised, means actuated by lateral movement of the receptacle on to a platform to cause said filling means to open, means including a solenoid switch actuated by the weight of a filled receptacle on said platform to cause the platform to lower and the filling means to close, a material feeding device associated with said filling means and operated 115

during the open period of said filling means, and a rotary reservoir supporting said filling means and by its movement causing operation of said feeding device.

- 5 8. In a receptacle filling machine, a rotary reservoir, a plurality of discharge chutes carried thereby, an agitator supported within said reservoir and adapted to be engaged by portions of said rotary reservoir to cause 10 said agitator to stir material in said reservoir, said agitator having a configuration which permits of portions thereof entering the chutes of said reservoir, feeding devices in the chutes of said reservoir placed in 15 operation at intervals during the rotation of said reservoir, discharge tubes carried by said chutes, and means actuated by the weight of the receptacle and its contents in said machine for simultaneously controlling

the discharge from said tubes and the intermittent operation of said feeding device. 20

9. In a receptacle filling machine, a rotary reservoir, circumferentially disposed chutes carried thereby, a feeding device in each chute, tilttable means adapted to be adjusted to cause operation of said feeding devices during rotation of said reservoir, means actuating said tilttable means, and controlled by the weight of a receptacle and its contents in said machine, an agitator in said reservoir and adapted to extend into the chutes thereof as said reservoir is rotated, means for rotating said reservoir, and means adapted to simultaneously adjust said tilttable means and control the discharge from 25 30 35 said chutes.

In testimony whereof I affix my signature.
GEORGE W. BLAKE.
